Attorney

UNITED STATES PATENT OFFICE.

ARTHUR P. ARMINGTON, OF WILLOUGHBY, OHIO.

SCRAPER DRAFT GEAR.

Application filed November 6, 1928, Serial No. 146,651. Renewed March 7, 1929.

This invention relates to draft gears for soil or earth moving machines such as are commonly known as scrapers and capable, while being pulled or dragged along the surface of the earth, of scooping a load of earth into a receptacle or bucket which forms a part of the scraper, transporting the load to the location desired, and there dumping the same; all of these operations being controlled at the will of the operator of the motive means, such as a tractor, by which the scraper is advanced through suitable connection therewith.

Ordinarily in a scraper of the type to which reference has been made, the bucket and its supporting and controlling means are designed and arranged to produce a predetermined motion of the bucket more or less of a scooping nature for the purpose of loading the same; this motion being non-variable, at least non-variable without adjustment requiring the use of tools, idleness of the scraper, and attending inconvenience.

In the use of such a scraper a very wide range is encountered both as to the nature and condition of the soil to be handled. As the bucket advances during the loading operation its tractive resistance rapidly increases due to the added weight, resulting in a tendency to dig into the soil the more deeply when the least desirable. Moreover an adjustment suitable for handling hardened clay for example, would be inefficient in handling soft loam, and likewise, an adjustment intended for efficient use in loose sand would be impossible of employment in an earth or soil presenting frequent large boulders; in the one case a great inefficiency results from the inability of the bucket to become completely loaded, and in the other case resulting in frequent stalling of the scraper with its traction means, or what is more serious, failure of some part of the scraper mechanism.

It is an object of my invention to provide a means for automatically regulating the "bite" of the bucket according to the amount of load therein, the instant nature of the soil encountered, and in general therefore according to the resistance of the bucket to tractive pull, and to this end and more specifically, to provide a novel arrangement whereby the lip of the bucket which enters the soil during the loading operation may be automatically adjusted in angularity cor-

respondingly as the resistance of the soil to the bucket lip is lessened or increased.

A further object of the invention is to proportion and arrange the parts whereby the automatic adjustment of the bucket lip will be of a smooth governing nature as distinguished from the hunting action which is found to be present in other automatic draft gears; that is, whereby when the scraper is used the cut taken will leave approximately a plane surface as distinguished from the number of spaced transverse ridges which result where other scrapers having automatic adjustment are employed.

A still further object of the invention is to provide a scraper having the fewest number of parts, having a simple arrangement of parts, and one wherein the stresses imposed upon the parts are cared for in the most direct manner possible.

The exact nature of the invention will be apparent from the following description taken in connection with the following drawings, in which Fig. 1 is a side elevation of a scraper in which my invention has been incorporated, the component parts thereof being shown as at the beginning of the bucket loading operation; Fig. 2 is a similar view showing the parts as at the end of the loading operation; Fig. 3 is a similar view showing the parts as in the dumping operation and Fig. 4 is a plan view, partly broken away, of the parts in the position of Fig. 3.

The type of scraper chosen for illustration and specific description of my invention is of the "run around" bucket type commonly known as the "Fresno" type, and comprises principally a bucket 1 of the usual generally cylindrical conformation, pivotally secured axially as at 2 with a draft gear including a yoke or bail having side members 3 adapted to be connected through suitable means to be described with a tractive means such as an automotive tractor. A hardened steel lip 5 extends laterally to form a flat portion of the bucket adapted to assume, when the bucket is in loading position, an approximately horizontal position at the bottom of the bucket, the bucket being provided with side plates 6, and a back plate 7. The bucket is strengthened at each end by a circular runner member 8 on which are adjustably secured a pair of projections 9 and 9' for a purpose to be described. The members 3 each extend from one side of

110

the bucket forwardly and according to my invention to fixed connection with a tubular torque member 10 positioned laterally therebetween.

5 Upon the yoke adjacent the forward portion of the bucket and carried by a pair of bracket plates 11 is a transverse rock shaft 12 upon which is secured a control lever 13, the outer ends of shaft 12 carrying a pair of 10 detent arms 14 in the planes of the projections 9 and 9'. An arm 15 forms with the lever 13 a bell crank, and is in engagement with a plunger 16 urged upwardly by the spring 17 whereby the control lever, and 15 hence the detent arms 14, are urged to the position shown in the figures in the path of the projections 9 as the bucket moves about its axis 2 and tangent to the runners 8. A control line 18 is secured with the upper 20 end of the lever 13 and extends to the tractive means to which the scraper is secured. Rearward motion of the lever 13 is limited by a pair of stops 19 secured to the bracket plates 11 to engage the detent arms 14, and 25 the brackets 11 are preferably adjustable on the yoke.

To this end each member 3 is provided with a longitudinally extending slot 3^a through which passes a bolt 20^a secured with 30 its bracket plate 11. Thus by loosening the bolt 20^a its bracket 11 may be adjusted by turning the set screw 20, after which the bolt 20^a may be retightened and the axis of the shaft 12 thus resecured in its adjusted 35 position; whereby the loading position of the bucket may be adjusted.

The general method of operation and control of the bucket for effecting loading and unloading thereof will be evident; upon forward motion of the draft gear the tendency 40 of the bucket is to roll forwardly upon the ground, that is to rotate in a clockwise direction, Figs. 1, 2 and 3, about its axis 2 as the same advances. The projections 9 are so 45 positioned upon the members 8 as to be engaged by the detent members 14 to secure the bucket in the loading position; the projections 9' being adjusted to secure the bucket in the dumping position. Hence, assuming 50 the bucket in the loading position as indicated in Fig. 1, the scraper is dragged forward until the bucket accumulates a load, after which movement of the scraper as to the dumping location may proceed without 55 substantial alteration in the load.

When the dumping location is reached a pull upon the control line 18 releases the detent levers 14 from the projections 9 allowing the bucket to roll upon the members 8 to 60 dumping position (Fig. 3) the spring 17 returning the detent arms to a position to engage the projections 9' to maintain the bucket in the dumping position. After the 65 load is emptied, the scraper is returned to the loading location by dragging it with the

bucket thus maintained in the dumping position and supported clear of the ground upon the members 8. To reload the bucket a second pull upon the control line 18 effects disengagement between the members 14 and 70 9' allowing the bucket to roll to loading position, proper reengagement of members 14 and 9 serving to maintain loading position of the bucket as before.

It is common practice to secure the draw 75 bar of the tractive means immediately with the yoke, so that the bucket is angularly immovable in either dumping or loading position. According to my invention however, I obtain an automatically regulated angular movement of the bucket in its loading position, providing joints 21 between the longitudinally extending members of the yoke and the inwardly inclined members 22. The forward extremities of the members 80 22 are secured as at 23 with a corresponding pair of members 24 which extend rearwardly between the members 22 to pivotal connection with the transversely extending torque member 10 coaxial with the pivots 21. 90

A tongue 25 rigidly secured with the torque member 10 extends forwardly thereof between the lever 24 to a point above the axis of the pivot 23, whereby angularity between the two draft structures is limited. 95 Thus while the members 3, 10, and 25 form a yoke draft structure in primary relationship with the bucket, so do the members 22 and 24 form a secondary draft structure in angular connection with the yoke and forming therewith in effect a unitary draft structure of yoke form jointed along the axis of the pivots 21.

Secured upon the members 24 are strut members 26 forming a rigid A frame terminating upwardly in an axial point 27 upon which is fulcrumed a bell crank lever 28, one arm of which is in connection by means of a link 29 with the tongue 25 as indicated. The opposite arm of the lever 28 is pivotally secured as at 30 with the rear end of a draft link 31, the forward end of which carries the draft link 4 and is positioned with respect to the member 24 by the link 32, whereby the forward end of the secondary draft 110 structure is substantially limited in vertical relationship with respect to the drawbar. The arrangement is such that relative longitudinal movement between the drawbar and the draft structures will be converted into 115 120 relative angular movement at the joint between the draft structures. A heavy spring 33 is provided, indicated as secured in tension between the draft link 31 and the A frame 26, whereby the draft link is strongly 125 urged rearwardly with respect to the members 24, to maintain the unitary draft structure in straightened relation.

It will be noted that the draft gear parts are so proportioned and arranged that, in 130

what might be considered their normal or straightened relation as in Figs. 1 and 3, the joint 21 lies substantially in the plane of draft, that is, in the same plane with the 5 axle means 2 and the draft eye 4; and the joint is medial or approximately midway of the draft gear link whereby if the joint is broken, as upwardly, the double yoke structure will be shortened, and the bucket will 10 be correspondingly tilted, as upwardly.

The result of the arrangement described is that normally the draft gear will function as a solid unit, under light load conditions the members retaining their relationship as 15 shown in Figs. 1 and 3. Presupposing, however, the bucket fully loaded or an obstacle of abnormal resistance to be encountered by the lip of the bucket, the draw bar will be moved forwardly with respect to the bucket, 20 tilting the bell crank 28 clockwise about its axis 27 to raise the tongue 25, "break" the unitary draft structure along the axis of the pivots 21, and hence slightly but with great force tilt the bucket to elevate the 25 lip 5; all against the resistance of the spring 33, the parts assuming a relation similar to that indicated in Fig. 2. Vertical motion of the tongue 25 is limited by its forward extremity engaging either of the axis bolts 30 23 or 27.

The advantage of this action is obvious. As the resistance of the bucket to forward movement is increased beyond a predetermined maximum, adjustable by adjustment 35 of the spring 33 as by the nut 34—either by the bucket attaining a loaded condition or by the lip of the bucket meeting a portion of hard earth, a boulder, tree root, or the like,—my draft gear is flexed as it were, 40 both somewhat relieving the draw bar stress and what is more important, effecting a rearward tilting motion of the bucket about its axis 2 to raise the lip thereof, allowing the bucket to ride up to the surface of the soil 45 if loaded, or to clear the obstruction if it be impassable, the adjustment of the bucket being effected automatically, dependent upon its tractive resistance.

It will be noted that whereas the center 50 of the bucket and therefore the bucket as a whole is arranged to lag bodily with respect to the draft eye, yet the relative motion or flexing of the draft structures in considerable measure reduces such lag; and in fact, owing 55 to the angular movement of the bucket upon its axis the actual distance between the bucket lip and the draft eye is not greatly varied. Therefore when the spring 33 is extended as during the operation of the 60 scraper, the bucket tilts about the forward edge of its lip rather than about its axis 2. The result is that when loading, where the obstruction to advance becomes sufficient 65 that the draft gear will automatically function as described, the bucket lip instead of

riding entirely out of the soil and then suddenly digging down into its again, will merely slightly change in angularity taking a cut of slightly less depth.

Attention is also called to the employment of the tubular torque member 10 whereby the yoke structure immediately secured with the bucket is maintained rigid at all times regardless of bending moment carried from the tongue 25 through the member 10 and to the side members 3. It will also be noted that the rock shaft 12 is closely adjacent the member 10, supported at its ends by the side members 3 closely adjacent the detent arms 14, which are so arranged as to be stressed in compression only.

What I claim is:

1. In a scraper of the class described, a bucket, a yoke structure therefor comprising a pair of side members having pivotal connection with said bucket, a transverse tubular torque member joining said side members, a tongue secured with said torque member and extending forwardly thereof, a secondary structure in pivotal connection with said yoke structure to form therewith a jointed yoke unit, movable operating means having supporting connection with said secondary structure and adapted for connection to a draw bar and associated with 95 said tongue to control the angular relation of said structures, and interengageable means carried by said side members and said bucket respectively and adapted to prevent rotation of said bucket in said yoke structure.

2. In a scraper having a bucket and means for controlling the same for effecting loading and unloading thereof, a draft gear comprising a yoke structure secured with 105 said bucket, a secondary structure in pivotal connection with said yoke structure, movable operating means having supporting connection with an end of said secondary structure and adapted for connection to a draw bar and associated with said yoke structure to control the angular relation of said structures, and means for yieldably maintaining said structures in predetermined angular relation and associated 110 with said operating means to yield upon operation thereof, whereby increased resistance to draw bar pull moves said operating means to produce relative motion between said structures and thereby elevate the lip 120 of the bucket from digging to non-digging position.

3. In a scraper including a bucket and means for controlling the same for effecting loading and unloading thereof, a draft gear comprising a yoke structure secured with 125 said bucket, a secondary structure in pivotal connection with said yoke structure to form therewith a jointed yoke unit, a draft link, the forward end of which extends ad-

70

5 jacent the forward end of said yoke unit, means connecting said ends to allow relative longitudinal motion therebetween, lever means supported by one of said structures and having connection with the rearward end of said draft link, means connecting said lever means with the other of said structures whereby resistance of said bucket to advance by said draft link effects angular movement between said structures to raise the lip of said bucket, and means for yieldably maintaining said structures in extended interrelation, and therefore said bucket in predetermined angular relation 10 with said draft link.

20 4. In a scraper including a bucket and means for controlling the same for effecting loading and unloading thereof, a draft gear comprising a yoke structure secured with said bucket, a secondary structure in pivotal connection with said yoke structure to form therewith a jointed yoke unit, movable operating means having supporting connection with the forward end of said 25 unit and adapted for connection to a drawbar and associated with both said structures to control the angular relation therebetween, and means for yieldably maintaining said parts with said structures in substantially straightened relation, said yoke unit being adapted for bending upward at its joint against the action of said yieldable means, whereby the lip of the bucket will be elevated.

30 5. In a scraper including a bucket and means for controlling the same for effecting loading and unloading thereof, a draft gear comprising a yoke structure secured with said bucket, a secondary structure in pivoted connection with said yoke structure to form therewith a jointed yoke unit, a draft link, the forward end of which extends adjacent the forward end of said yoke unit, means interconnecting said ends for 35 allowing relative longitudinal motion therebetween, lever means in pivotal relation with one of said structures and connected with the rearward end of said draft link, a member of the other of said structures extending adjacent said lever means, means connecting said member and said lever means whereby resistance of said bucket to advance by said draft link effects angular movement between said structures to raise 40 the lip of said bucket, and means for yieldably maintaining said structures in extended relation.

45 6. In a scraper comprising a bucket and means for controlling the same for effecting loading and unloading thereof, a draft gear comprising a primary yoke structure secured with said bucket, a secondary yoke structure in pivotal connection with said primary structure to form therewith a 50 jointed yoke unit, a drawbar the forward

end of which extends adjacent the forward end of said secondary yoke unit, means connecting said ends to allow relative longitudinal motion therebetween, a lever in pivotal relation with one of said structures and connected with the rearward end of said drawbar, a member of the other of said structures extending adjacent said lever, a link connecting said member and said lever whereby resistance of said drawbar to advance by said bucket effects angular movement between said yoke structures to raise the lip of said bucket, and means for yieldably maintaining said yoke structures in extended relation and therefore 55 said bucket and drawbar in predetermined angular relation.

7. In a scraper having a bucket and means for controlling the same for effecting loading and unloading thereof, a draft gear comprising a yoke structure secured with the bucket, a secondary yoke structure, said yoke structures having pivotal interconnection, means adapted to associate the forward end of said secondary yoke structure with draft means for support thereby, whereby a double yoke structure is had, with a joint medial of its length and substantially in the plane of draft whereby as the joint moves upwardly the double yoke structure will be shortened, and means for causing breaking of said joint upwardly dependent upon the draft magnitude whereby the bucket will be tilted rearwardly correspondingly.

8. In a scraper having a bucket and means for controlling the same for effecting loading and unloading thereof, a draft gear comprising a yoke structure secured with the bucket, a secondary yoke structure, said yoke structure having pivotal interconnection, means adapted to associate the forward end of said secondary yoke structure with draft means for support thereby, whereby a double yoke structure is had, with a joint medial of its length and substantially in the plane of draft whereby as the joint moves upwardly the double yoke structure will be shortened, one of said yoke structures having a portion extending beyond 105 said joint, and means carried by the other yoke structure and associated with said extending portion and adapted for association with said draft means for causing breaking of said joint upwardly dependent upon the 110 draft magnitude.

9. In a scraper having a bucket and means for controlling the same for effecting loading and unloading thereof, a draft gear comprising a yoke structure secured with the bucket, a secondary yoke structure, said yoke structures having pivotal interconnection, means adapted to associate the forward end of said secondary yoke structure with draft means for support thereby, 125

- whereby a double yoke structure is had, with a joint medial of its length and substantially in the plane of draft whereby as the joint moves upwardly the double yoke 5 structure will be shortened, means for limiting downward breaking of said joint, one of said yoke structures having a portion extending beyond said joint, and means carried by the other yoke structure and associated with said extending portion and adapted for association with said draft means for causing breaking of said joint upwardly dependent upon the draft magnitude.
10. In a scraper having a bucket and means for controlling the same for effecting loading and unloading thereof, a draft gear comprising a yoke structure secured with the bucket, a secondary yoke structure, a draft link adapted for connection with draft means and having movable supporting connection with the forward end of said secondary yoke structure, said yoke structures having pivotal interconnection where- 20 by a double yoke structure is had with a joint medial of its length, yieldable means for opposing relative movement of said draft link in the direction of draft, said primary yoke structure having a tongue ex- 25 tending forwardly of the joint between the yoke structures, and means carried by said secondary yoke structure and connecting said draft link with said tongue to break said joint upwardly as said draft link moves 30 in opposition to said yieldable means.
11. In a scraper having a bucket and means for controlling the same for effecting loading and unloading thereof, a draft gear comprising a primary yoke structure se- 35 cured with said bucket, a secondary yoke structure having pivotal connection with said primary yoke structure, a draft link adapted for connection with draft means, means movably supporting the forward end of said 40 secondary yoke structure on said draft link, whereby a double yoke structure is had with a joint medial of its length and sub- 45 stantially in the plane of draft whereby as the joint moves upwardly the double yoke 50 structure will be shortened, and operating means supported on one of said yoke structures and associating said draft link with the other of said yoke structures to break said joint upwardly dependent upon draft.
12. In a scraper having a bucket and means for controlling the same for effecting loading and unloading thereof, a draft gear comprising a primary yoke structure secured with said bucket, a secondary yoke structure having pivotal connection with 55 said primary yoke structure, a draft link having coupling means adapted for connection with draft means, means movably sup- 60 porting the forward end of said secondary yoke structure on said draft link, and oper- 65 ating means supported on one of said yoke structures and associating said draft link with the other of said yoke structures to yieldably maintain the joint between said yoke structures in the plane of said coupling 70 means and the connection between said primary yoke structure and said bucket, and adapted to break said joint upwardly de- 75 pending upon draft.
13. In a scraper having a bucket, draft gear connected therewith, means for controlling bucket movements for effecting loading and unloading thereof, said controlling means comprising projections on said bucket and means on said draft gear for engaging 80 said projections and including a rock shaft and detent arms thereon, and means for bodily adjusting said rock shaft on said draft gear to effect adjustment of said bucket in digging position.
14. In a scraper having a bucket, draft gear connected therewith, means for controlling bucket movements for effecting loading and unloading thereof, said controlling means comprising projections on 85 said bucket and means on said draft gear for engaging said projections and including a rock shaft with detent arms thereon and bracket means movably mounted on said draft gear and carrying said rock shaft, 90 whereby adjustment of said bucket in dig- 95 ging position may be effected.

Signed by me, this 18th day of October, 1926.

ARTHUR P. ARMINGTON.
